UNITED STATES PATENT OFFICE.

FRANK MILHENING, OF EVANSTON, ILLINOIS, ASSIGNOR TO J. MILHENING, INC., OF CHICAGO, ILLINOIS, A CORPORATION OF ILLINOIS.

DESIGN FOR A FINGER RING.

•61,050.

Specification for Design.

Patented June 6, 1922.

Application filed February 13, 1922. Serial No. 691. Term of patent 7 years.

To all whom it may concern:

Be it known that I, FRANK MILHENING, a citizen of the United States, residing at Evanston, in the county of Cook and State of Illinois, have invented a new, original, and ornamental Design for Finger Rings, of which the following is a specification.

In the accompanying drawing, forming part of this specification—

Figure 1 is a side elevation, Figure 2 an edge view, and Figure 3 a top plan view of a finger ring embodying the design.

I claim:

The ornamental design for a finger ring as shown.

FRANK MILHENING.
